UNITED STATES PATENT OFFICE.

FRANK K. WARD, OF WASHINGTON, DISTRICT OF COLUMBIA.

DESIGN FOR A JAR-STOPPER.

SPECIFICATION forming part of Design No. 21,465, dated April 12, 1892.

Application filed March 10, 1892. Serial No. 424,453. Term of patent 14 years.

To all whom it may concern:

Be it known that I, FRANK K. WARD, a citizen of the United States, residing at Washington, in the District of Columbia, have invented and produced a new and original Design for a Jar-Stopper, of which the following is a specification.

This design has for its object to provide a novel and ornamental stopper for milk or fruit preserving jars, whereby a distinguishing and handsome appearance is presented to the eye; and the leading feature thereof resides in a jar-stopper having central top and bottom approximately hemispherical protuberances vanishing in a lateral annular flange.

The design is illustrated by the accompanying drawings, in which—

Figure 1 is a side elevation of a jar-stopper, illustrating my design, a jar-body being represented by dotted lines; and Fig. 2 is a vertical central sectional view of the jar-stopper,

a jar being represented by dotted lines partially broken away.

In the accompanying drawings, the reference-numeral 1 indicates the central approximately hemispherical protuberance on the under side of the jar-stopper, and 2 indicates the central approximately hemispherical protuberance on the upper side of the jar-stopper. 25 These hemispherical protuberances vanish in a lateral annular flange 3, which is convex, as at 4, on its upper side around the protuberances 2.

What I claim is—

The design for a jar-stopper, substantially as shown and described.

In testimony whereof I have hereunto set my hand and affixed my seal in presence of two subscribing witnesses.

F. K. WARD. [L. S.]
